BEVERAGE CASE

Otis C. Coles, Jr., El Paso, Tex.

Application April 9, 1948, Serial No. 19,965

3 Claims. (Cl. 220—21)

1

The present invention relates to beverage cases and is particularly well adapted for use in the storage and transportation of beverages put up in bottles. Such cases, sometimes called "flats," usually each have cells for receiving two dozen bottles.

In the past such cases have generally been made of wood, which is highly susceptible to damage and destruction, and in use the cases become unsightly, since paint, trade-marks and other indicia applied to them wear off rapidly. This requires frequent repainting and restenciling if the cases are to present good appearance.

The principal objects of the invention are to increase the average life of cases of this general character, by rendering them more durable and sturdy; reduce fatigue in the handling of such cases by rendering the cases comparatively light in weight; and reduce production and maintenance costs of the cases.

These objects are in part accomplished by producing the outer shell of the case from sheet or molded material, such as metal or fiber, which may be die cut, stamped with trade-mark and other indicia, and crimped or molded in one operation.

Another object is to provide cases of this character, the bottoms of which are provided with ribs so positioned as to cushion the bottoms of the bottles when they are being placed in the case, and during transportation, so that the bottles are not likely to be broken or chipped, and to take up slack in the sheet or molded material and to give additional rigidity to the case.

A further object is to provide cases which may be freed of trash or foreign matter with comparative ease, and any damaged cell forming means within the case body, readily replaced when damaged. This is mainly accomplished by providing openings at the corners of the bottoms and sides of the cases, providing exits for trash and foreign matter, easily carried thru the openings by a flushing operation without the necessity of tilting or inverting the cases and by providing cell forming means which may be readily snapped into place and easily removed, in contradistinction to cell forming means mortised or otherwise permanently secured in place. The open corners of the case alleviate damage by denting or breakage due to rough handling.

Other objects and advantages will appear in the following detailed description of two highly satisfactory forms of my invention, taken in connection with the accompanying drawings, forming a part of this specification and in which drawings:

Fig. 1 is a view partly in side elevation and partly in central vertical section of a case constructed according to the present invention, a portion of a suitable cell forming means being illustrated in elevation and in place within the case.

Fig. 2 is a view partly in top plan, and partly in horizontal section of the case, with a portion of the cell forming means shown in plan.

Fig. 3 is a view similar to Fig. 1, but looking toward the end of the case.

Fig. 4 is a plan view of a suitable blank from which the body portion of the case may be made.

Fig. 5 is an enlarged, vertical sectional view on the line 5—5 of Fig. 2.

Fig. 6 is a fragmentary perspective view of the case looking toward the inside of one of the open or cut-away corners.

Figs. 7, 8 and 9 are views similar to Figs. 1, 2 and 3, respectively, showing a modified form of the invention.

Fig. 10 is an enlarged sectional view on the line 10—10 of Fig. 8.

In the drawings, and referring first to the form of invention shown in Figs. 1—6, inclusive, the case comprises a body portion 11, an upper reinforcing band 12, a lower reinforcing band 13 and a unitary cell forming means 14.

The body portion 11 comprises a generally rectangular bottom 15 and side and end walls 16 and 17 respectively. This body portion may be formed from sheet material, such as metal, cut to form a blank 18 shown in Fig. 4 having preferred characteristics as hereinafter noted. The material may be of the color, or coated with colored material, or otherwise treated so that it is distinctive and may be readily recognized from the color as that adapted by the particular user to distinguish his brand of beverages from others. Trade-marks and other indicia, not shown in the drawings, may be economically impressed, or cut in the material during the same production stroke whereby the blank is struck from the sheet stock. In this way painting or decorating after manufacture is avoided.

Since it is common practice to provide cases or flats to receive twenty-four bottles arranged in four rows of six bottles each, the bottom is preferably elongated and generally rectangular in shape and preferably provided with four longitudinally extending upstruck, spaced, parallel ribs 20, each preferably of inverted V-shaped cross section, to provide a crown 21, as shown in Fig. 2, 3 and 5, and merging at substantially triangular shaped ends 22, into the main body of the bottom short of the ends thereof as shown

in Figs. 2 and 6. These ribs serve to cushion the bottoms of the bottles when they are being placed in the case and during transportation, since the case body may be made of material of such gauge as to yield slightly or have a limited amount of resiliency at the ribs when the bottles are dropped thereupon or vibrated during transportation. The ribs also take up slack in the sheet or molded material and give additional rigidity to the bottom as a whole.

The bottom 15 is preferably provided with notches 23 at its corners thru which foreign material, such as trash, may be flushed or brushed, and the side and end walls preferably extend from the bottom between the margins of the notches, as shown in Fig. 4, whereby openings 24 are provided at the corners of the case body portion, as shown in Figs. 3, 5 and 6. In this way damage by denting or breakage, due to rough handling, is alleviated since there are no rectangular bends of the body portion material at corners.

The upper reinforcing band 12, may be made from heavy wire or rod material, bent to generally rectangular, elongated formation, in the example shown. This applies also to the lower reinforcing band 13. In effect, the corners are rounded as indicated at 25 so that in handling the cases or flats, no sharp corners or edges are presented at the upper portion of the case.

Each end wall 17 has a cut away portion 26 intermediate its ends 27 open to the top of the wall, providing a pair of upstanding tongues 28, the upper margins of which are curled over, in an inward direction, and about the upper reinforcing band 12, as indicated at 29, to provide a handhole 30 at each end wall beneath a run 31 of the reinforcing band, which latter serves as a handle for the case. Each wall 17 is also preferably provided with slits extending from and below the sides of the handhole 30 and the material between the slits is bent over to form a reinforcing flange 33.

The upper marginal portions of the side walls 16 are also curled over, in an inward direction, and about the upper reinforcing band 12, as indicated at 32. Thus these curled portions 29 and 32 form beading at spaced lengths about the upper margin of the case.

The lower reinforcing band 13 may also be made of heavy wire or rod material, and is disposed at the inside of the body portion 11 at the juncture of the bottom 15 with the walls 16 and 17, and is preferably of generally rectangular elongated shape so as to reinforce the lower portion of the body 11. The corner portions are rounded as indicated at 34 and transverse the space between the ends of the walls 16 and 17. The reinforcing band may be held in place by providing inverted U-shape cuts 35 in the walls 16 and 17 adjacent the band, and the material within the bounds of each of these cuts is curled inwardly and around the band as indicated at 36.

In my copending application for patent on bottle openers for beverage cases, filed April 9, 1948, Serial No. 19,967, is shown, in detail, a suitable unitary cell forming means 14 particularly well adapted for use with the types of cases shown in the present application. Generally it comprises a plurality of coils of wire 37 forming cells 38 in which bottles, not shown in the drawing, may be disposed. The coils may be connected in any suitable manner, such as by clips 39 embracing adjacent convolutions of the coils. This arrangement provides a flexible or resilient

unit which may be slightly compressed vertically and horizontally so that it may be sprung into place resting upon the upper surface of the lower band 13, where it is spaced above the bottom 15, and beneath the upper band 12, in contact with the underside of the inwardly extending beading 29—32, as shown in Figs. 1 and 3, detachably retaining the device in place in the hollow of the body portion 11.

10 By thus supporting and retaining the resilient cell forming means in the case, the lower portion of the former does not contact the case bottom and foreign matter, such as bits of paper, match sticks and the like, may be more readily washed from the case without removing the cell forming means, and if necessary, the latter may be readily removed from the case without loosening any fastening devices.

The ribs are disposed so that when the means 14 is in place the cells 38 thereof are substantially centered over the ribs, with the advantages hereinbefore set forth.

In the example shown in Figs. 7-10, inclusive, the body portion 40 may be substantially the same as in Figs. 1 to 6, inclusive, with the exception that the upper reinforcing band 41 of this modification is slightly larger and the upper marginal portions of the side walls 16 and of the tongues 28 are curled over, in an outward direction, about the upper reinforcing band 41 as indicated at 42 and 43, respectively and suitable means 44, carried by the lower reinforcing band 13, is provided, detachably connecting the cell forming means 14 in the hollow of the case. In the example shown, the means 44 may comprise a plurality of clips, each comprising an arcuate or C-shaped portion 46 embracing the band 13, and upstanding crimped arms 47 carried by the portion 46 embracing a lower portion of the cell forming means, shown more in detail in Figs. 9 and 10. In this way the cell forming means 14 may be forced into position so as to be supported upon these clips and may be readily removed by exerting a slight pull upon the cell forming means since the upper reinforcing band 41 does not overlie the said means.

In each of the forms of cases herein disclosed the construction may be comparatively light in weight, due to the use of sheet material for the bottom and walls of the main body and heavy wire or rod stock for the reinforcing bands. The preferred construction is such that, upon removal of the cell forming means, the case bodies may be readily cleaned as by brushing or flushing accumulated trash and foreign matter from the bottoms, such findings egress thru the notches 23 and/or openings 24 at corners. Injury to persons handling or brushing against the cases is not apt to occur, since no sharp corners are presented and the cases are not likely to be damaged even tho roughly handled since the corners of the reinforcing bands are rounded and the side walls as well as the material from which the bottom is made terminate at spaced distances from what is usually the corners of ordinary cases or flats.

While I have herein disclosed two forms of cases particularly well adapted for receiving bottles arranged as is common practice in a plurality of rows with the bottles in any one row in substantially side by side relation to those in any next adjacent row, certain features of the invention may be utilized in the production of cases or flats where the bottles of any row are in staggered relation to the bottles of any next adjacent row

as disclosed in my copending application for patent on beverage cases filed concurrently herewith, Serial No. 19,966.

I claim:

1. In a beverage case, a body portion comprising a generally rectangular bottom and side and end walls integral with said bottom, and upper and lower rectangular reinforcing bands, said bottom provided with notches at its corners and said side and end walls extending from said bottom between the margins of said notches whereby openings are provided at the bottom and corners of the case body portion, the upper marginal portions of the side and end walls curled over and about the upper reinforcing band to 15 form a beading at spaced lengths about the upper margins of the case, and the lower reinforcing band disposed at the inside of the body portion at the juncture of the bottom with said walls and spaced from the bases of said notches in the bottom, so that foreign matter may be flushed from the case thru said bottom notches, and with the corners of the upper and lower reinforcing bands, traversing the space between the ends of said walls at the corners of the case.

2. In a beverage case, the combination of a body portion comprising a generally rectangular bottom and side and end walls, an upper rectangular reinforcing band about which the upper marginal portions of said walls are curled over in an inward direction, and about the reinforcing band providing inwardly extending beading at the top of the case, and a lower rectangular reinforcing band disposed at the inside of the body portion at the juncture between the bottom and said walls; and a resilient cell forming means in the hollow of said case removably supported upon the upper portion of the lower reinforcing band and removably sprung under and engaging the lower portion of said inwardly extending beading.

3. In a beverage case, the combination of a body

portion comprising a generally rectangular bottom and side and end walls integral with said bottom, an upper rectangular reinforcing band about which the upper marginal portions of said walls are curled over in an outward direction, and about the reinforcing band providing an outwardly extending beading at the top of the case, and a lower rectangular reinforcing band disposed at the inside of the case at the juncture between the bottom and said walls; a cell forming means in the hollow of the case above said lower reinforcing band and engaging the walls of said body portion; and means carried by said lower reinforcing band detachably connecting said cell forming means in the case.
